UNITED STATES PATENT OFFICE.

JOHN CARTWRIGHT TRIGUE CROWDEN, DECEASED, LATE OF BANDIKUI, RAJPUTANA, INDIA, BY MARY CROWDEN AND ARTHUR FRANK BARNARD EXECUTORS, BOTH OF DUNSTABLE, ENGLAND.

LOCK.

Application filed October 3, 1921. Serial No. 504,973.

To all whom it may concern:

Be it known that we, MARY CROWDEN and ARTHUR FRANK BARNARD, both subjects of the King of Great Britain, and residents 5 of Southdene, Dunstable, in the county of Bedford, England, and Albion House, Dunstable, in the county of Bedford, England, respectively, are the legal representatives of JOHN CARTWRIGHT TRIGUE CROWDEN, de-

ceased, lately of the Lawn, Bandikui, Jaipur State, Rajputana, India, who has invented certain new and useful Improvements in Locks (for which he has filed an application 10 in India, October 4th, 1920), of which the following is a specification.

This invention relates to locks particularly adapted for use in locking the doors of railway vehicles, stores, magazines, safes and so forth.

According to the invention a locking spindle is adapted to be turned into the locking position for engagement with a locking bracket and is adapted to be locked in the locked or unlocked position by means of a 20 key of which the movement is controlled by means of a series of combination rings. The key is adapted to engage with one of a number of sets of recesses in the brackets in which the spindle is rotatably mounted, the 25 key fitting into a keyway in the spindle. The key is also provided with projections with which engage a series of combination rings which can be turned around the spindle and the key and which are each provided 30 with a recess. In order to insert or withdraw the key the recesses must all be brought into alignment with the set of recesses in the brackets with which the key is in engagement or is to be brought into engagement.

In the accompanying drawings is illustrated by way of example one form of construction according to the invention.

Figure 1 is a front elevation, Figure 2 is a vertical section on the line 2—2 of Figure 45 10, Figure 3 is a detail view, Figure 4 is a side elevation of the key, Figure 5 is a plan of one of the combination rings, Figure 6 is a section on the line 6—6 of Figure 5, 50 Figure 7 is a plan of the lock, Figure 8 is a cross section on the line 8—8 of Figure 2, Figure 9 is a cross section on the line 9—9

of Figure 2, Figure 10 is a side elevation and a part section on the line 10—10 of Figure 1, and Figure 11 is a cross section on the line 11—11 of Figure 2.

Referring now to the drawings the main spindle, 1, of the lock is supported in position and attached to the door or other suitable part of the vehicle, safe and the like 60 to be locked by means of brackets 10, and 11, arranged one in front of the other, as shown in Figure 10 for example, which are secured in position by bolts or rivets 15, 16, 17 and 18. The lower end 40 of the spindle 65 1, which forms the actual locking member is oval or elliptical in shape so that when its major axis lies in a plane at right angles to the front face of the door or the like it can be passed between the jaws 41 of the locking 70 bracket 13 secured to a fixed part of the vehicle or the like. In the locking position the major axis of the lower end 40 of the spindle lies in a plane parallel to the door or the like. The spindle 1 passes through 75 the holes, 19 and 20 in the brackets 10 and 11, and is retained in position by means of a collar 21, provided thereon and adapted to be held between the two brackets 10 and 11. The spindle 1 is capable of rotation in 80 these holes 19 and 20 its rotation being controlled and limited by a stop 14 fixed to the bracket 11 and engaging with a recess 23 in the collar 21. The spindle 1 is turned by means of the squared portion 24 thereon and 85 may be turned either by hand or by a suitably shaped tool adapted to fit on the squared portion 24. The spindle 1 after being turned is locked in the required position by means of the key 2 which works in 90 a keyway 25 formed in the spindle and also in recesses 26, 27 and 28 29, in the brackets 10 and 11 respectively. When the key is placed in the keyway 25, and in the recesses 95 in the brackets 10 and 11 it will be seen that the spindle is prevented from turning in the holes in the brackets 10 and 11 as long as the key 2 is held in this position. The key 2 is held in this position by means of combination rings 3, 4, 5, 6 and 7 and which 100 can be turned around the spindle 1 but are prevented from sliding thereon by means of a guide cap 8, and a lock nut 9. The rings 3, 4, 5, 6 and 7 are notched as shown

at 46 in Figures 5 and 6 to allow of the passage of the key 2. The guide cap 8 and the lock nut 9, are also similarly notched for the same purpose. It will therefore be seen that when the notches in the members 3, 4, 5, 6, 7, 8 and 9 are in alignment with the keyway 25 in the spindle 1, and also with the recesses 26 and 28, or 27 and 29, in the brackets 10 and 11 the key 2 can be passed straight through these parts until it comes into contact with a bracket 12. This bracket 12 is preferably secured to the bracket 11 and serves to limit the downward movement of the key and also to cover the recesses in the bracket 11. The rings 3, 4, 5, 6 and 7 when turned around the spindle 1 remain in engagement with the key as the shoulders formed thereon by the recesses 47 pass through slots 30, 31, 32, 33 and 34 in the key 2. It will therefore be seen that if, after inserting the key 2 the rings are rotated, the key cannot be withdrawn until all the notches 46 in all the rings are again placed in alignment with the key.

In order that the rings may readily be set in the required position for inserting or removing the key, they are provided with suitable markings such as letters, figures or signs, which are stamped or otherwise marked on the outer circumference thereof. The letters on the separate rings are adapted to be arranged in a series to form a combination which is known to those persons deputed and authorized to operate the lock. When the letters forming the combination have been arranged in a straight line between the two arrows 35, 36, Figure 1 the key 2 may be inserted or withdrawn. One of the arrows is preferably marked on the guide cap 8 and the other on the bracket 10. It will thus be seen that when a ring is so placed that the notch 46 in it is in a straight line with the key 2 a single letter will be contained in the straight line between the arrows. This letter therefore forms the combination or operating letter, for that particular ring and in order that it may be known readily for the purpose of arranging the combination it is stamped or otherwise marked in a convenient position on the top or bottom face of the ring.

The key 2 is made thicker at its upper end as shown at 52 so as to cover the end of the slot in the lock nut 9, and thus prevent the introduction of a feeler or a thin piece of wire or the like for the purpose of picking the lock by ascertaining the position of the slots in the rings. A hole is provided at 37 in the lug of the key 2, for the purpose of assisting the operator in withdrawing the key from the lock. A pin is passed through this hole and by means of a conveniently shaped lever acting on this pin and against the top of the lock nut 9 the key may be withdrawn readily

when the rings are in the correct position. This lever may be incorporated with and made part of the wrench, already referred to, which is adapted to fit on the square end of the spindle 1. This hole also serves as a means whereby a seal may be affixed to the lock. A cord, string or wire can be threaded through this hole and also through the hole 38, in the squared end 24 of the main spindle 1, and the seal may then be affixed to this cord, string or wire. Another hole is also provided at 39, in the lug of the key 2, for the purpose of attaching a chain or other convenient fastening whereby the key may be securely attached to the lock and its loss prevented when it is withdrawn from the lock.

The locking bracket 13, may be attached in any convenient position on the floor of the vehicle, safe and the like, or it may be attached to a cross bar which may extend across the door of such vehicle, safe and the like.

When fitted to railway vehicles, in which case there would be one lock on each side of the vehicle, each lock would be distinctively numbered as shown at 45, in Figure 1.

The two sets of recesses in the brackets 10 and 11 namely the recesses 26, 27 and 28, 29 are preferably arranged 90° apart so that the lock may be locked in both the locked and in the unlocked positions. The lock is locked in the locked position when the major axis of the oval or elliptical end 40, of the spindle 1 is at right angles to the jaws 41, of the locking bracket 13, and it is locked in the unlocked position when the minor axis is at right angles to the jaws. The capacity for being locked in the unlocked position is provided for use when the door is to be left open and unlocked and also when it is required to put the lock out of action for any reason.

The hole, 42, in the guide cap 8, is of a convenient irregular shape corresponding to the shape of the lower end 43 of the spindle, 1, as shown in Figure 7. The object of this is to prevent the guide cap 8, being put on the spindle in the wrong position. The lock nut 9, is provided with flat sides as shown at 44 to fit a wrench, spanner or other convenient tool whereby the nut may be screwed or unscrewed for the purpose of detaching the guide cap 8, and the rings 3, 4, 5, 6 and 7 and also for obtaining access to the interior of the lock for cleaning and repairing purposes. This wrench or spanner may also be incorporated with and made part of the wrench and lever above referred to.

The combinations formed by the rings may be varied by arranging the rings in different orders on the spindle 1, and a number of different combinations may thus

be obtained. The marks on the combination rings are arranged in a certain order in accordance with any convenient and prearranged master combination so that the lock 5 can only be opened after ascertaining the correct combination. This master combination may, for example, consist of an arrangement of certain letters, figures or signs on the rings which bear a certain 10 relation to the operating letters, figures or signs for those rings and by means of which the said operating letters, figures or signs may be ascertained. The master combination may be drawn up and arranged in 15 any convenient manner and shall itself be capable of variation in order that it may remain secret and unknown except to those persons who are authorized to possess such knowledge.

20 The combination rings are recessed as shewn at 47 in Figure 6 and at 47, 48, 49, 50 and 51 in Figure 2 to allow of the engagement of the rings with the key 2 and for the spacing of the slots 30, 31, 32, 33 and 25 34 in the key 2.

The parts of the mechanism may be made of any suitable material and are hardened, where necessary, to resist wear. The parts, if required may be made of steel or iron 30 treated so as to render it proof against rust or they may be made of nonrusting material.

If desired the lock may be enclosed inside a cover of cloth, tarpaulin, leather or 35 other suitable material for the purpose of protecting it from rain, damp, dust, acid atmosphere and the like.

Having thus described our invention what we claim as new and desire to secure by Letters Patent is:—

1. A lock comprising a locking bracket having a slot therein terminating in a circular aperture of larger diameter than the width of the slot, a locking spindle and 45 brackets for rotatably supporting the same, one end of said spindle being of a cross section wider in one plane than in a plane at right angles thereto and adapted to be passed through the said slot into the circular 50 aperture said spindle having a key-way therein, said brackets having a plurality of sets of recesses therein in different angular positions, a key fitting in said key-way and adapted for engagement with the recesses 55 in the brackets, the sets of recesses in the brackets being so arranged that when the key and spindle are turned so that the key engages with one set of recesses the spindle is locked in a position to enable the end 60 thereof to pass through the slot in the locking bracket, whilst when the spindle and key are turned so that the key engages with another set of recesses the spindle is locked in a position to prevent its lower end from 65 passing through the slot in the locking

bracket, and means for locking and releasing the key.

2. A combination lock, comprising brackets with sets of recesses formed at intervals of 90° therein, a locking spindle having a key-way therein rotatably mounted in said brackets one end of said spindle being elliptical in cross section, a key with recesses therein fitting said key-way and adapted for engagement with said sets of recesses, a locking bracket having a slot therein terminating in an aperture, the elliptical end of the spindle being adapted to be passed through said slot into the aperture and then turned so as to prevent its passage from the aperture and through the slot, a plurality of combination rings each with a notch therein rotatably fitting around the spindle and the key, the notches being adapted to permit of sliding movement of the key when the notches in all the combination rings are in alignment, whilst the combination rings in other positions engage with the recesses in the key and prevent sliding movement thereof, a cap fitting on said spindle and preventing lateral movement of the combination rings, and a lock nut for securing the cap in position.

3. A combination lock, comprising a locking bracket having a slot therein terminating in a circular aperture of larger diameter than the width of the slot, a locking spindle for engagement with said bracket, said spindle having a keyway therein, a plurality of combination discs each with a notch therein, said combination rings being rotatably supported on said spindle, brackets in which the spindle is rotatably mounted, each of said brackets having a plurality of recesses therein in different angular positions, a key fitting in said keyway and adapted for engagement with the recesses in the brackets, the sets of recesses in the brackets being so arranged that when the key and spindle are turned so that the key engages with one set of recesses the spindle is locked in a position to enable the end thereof to pass through the slot in the locking bracket, whilst when the spindle and key are turned so that the key engages with another set of recesses the spindle is locked in position to prevent its lower end from passing through the slot in the locking bracket, and means for locking and releasing said key.

4. A lock comprising a locking bracket having a slot therein terminating in a circular aperture of larger diameter than the width of the slot, a locking spindle and brackets for rotatably supporting the same, one end of said spindle being of a cross section wider in one plane than in a plane at right angles thereto and adapted to be passed through the slot into the circular aperture, said spindle having a keyway therein, said brackets having a plurality of

sets of recesses therein in different angular positions, a key fitting into said keyway and adapted to lock the spindle to the brackets, a plurality of combination rings rotatably mounted around said spindle and key, said combination rings being adapted to lock the key in engagement with the brackets or to permit of its release therefrom, and means for limiting the turning movement of the locking spindle.

MARY CROWDEN,
A. FRANK BARNARD,
Executors of John C. T. Crowden, deceased.
